UNITED STATES PATENT OFFICE.

GEORGE H. FRASER, OF BROOKLYN, NEW YORK.

MACHINE FOR CRUSHING OR GRINDING.

Original application filed March 16, 1905, Serial No. 250,474. Divided and this application filed January 31, 1917, Serial No. 145,690. Renewed December 15, 1922.

To all whom it may concern:

Be it known that I, GEORGE H. FRASER, a citizen of the United States, residing in the borough of Brooklyn, county of Kings, city 5 and State of New York, have invented certain new and useful Improvements in Machines for Crushing or Grinding, being a division of my application filed March 16th, 1905, Serial Number 250,474, renewed July 10 3, 1916, renewal Serial No. 107,467, patented April 10, 1917, No. 1,222,382, of which the following is a specification.

This invention relates to machinery for crushing, grinding or pulverizing materials, 15 and aims to provide certain improvements therein.

The invention relates more particularly to rock crushers of the type having a plurality of crushing rolls within an annular die in 20 which the crushing is effected between the periphery of the rolls and the inner face of the die. One example of this type of crusher is shown in the patent of H. L. Kent, granted May 7, 1901, No. 673,856, in which the die 25 revolves and is held in position by the rolls, which latter are carried by shafts held in bearings at the outside of the casing, the bearings being carried by slideways and pressed outwardly by springs, so that the 30 rolls may slide in and out radially of the ring. The top roll in this patent is shown as supporting the ring yieldingly, and the sliding frames carrying the shafts are of sectional construction, and both guide the 35 shafts and transmit the crushing pressure from the springs to them.

My present invention aims to provide an improved crusher or pulverizer especially applicable to this general type.

40 To this end in carrying out my present invention in its preferred form, I provide an improved arrangement of die and rolls, improved means for carrying the roll shafts, improved means for guiding such shafts, 45 means for transmitting all or part of the crushing thrust from one roll to another in whole or in part, and various details of improvement in the construction and arrangement of the various parts of the crusher, all 50 of which will be hereinafter more fully set forth with reference to the accompanying drawings, in which Fig. 1 is a fragmentary side elevation of a pulverizer embodying the preferred form of my invention, the view 55 being partly broken away to show two of

the yokes in mid-section, and Fig. 2 is a rear elevation partly in vertical axial mid-section.

Referring to the drawings, A is the casing, B is the ring or die, C, C¹ and C² are the crushing rolls, D, D¹ and D² are their shafts, E, E¹ and E² are their bearings, S, S¹ and S² are the crushing springs, and d, d¹ and d² are adjusting screws.

The casing encloses the ring and rolls and 60 supports them. The top roll in the construction shown carries the ring by acting against the inner face, and the other rolls press outwardly against the inner face to crush the rock between their peripheries and such face. Their pressure may be adjusted by 65 the springs and adjusting screws. The ring and rolls are driven in any suitable manner, as by driving the shaft D by the pulley F for example. The feed delivers the 70 rock on to the inner face of the ring, and the crushed rock flows off the sides of the ring and falls out through an opening j⁶ in the bottom of the casing. The casing is 75 made sectional to permit opening, as by being constructed as a base or bottom shell a and a cover or top shell b.

I will now describe in detail the preferred 80 form of my improvements as illustrated in the drawings.

According to one feature of improvement, I preferably guide the bearings for the several shafts by a swinging guide or pivotal connection, so that each can oscillate relatively to a predetermined axis if its movement radially of the ring is necessary. I 85 prefer to so guide each shaft bearing, and to carry all from the casing, which for this purpose I preferably provide with a transverse shaft g, the shaft g being connected to the top bearing by links r⁴ on opposite sides of the casing, and the bearing E being connected by links s⁴ to the lower bearings E¹ and E², so that each of these lower 90 bearings is yieldingly or movably sustained or supported pivotally from its center from the bearing E. These connections permit the bearings to rock toward and from the center of the ring, but support them against thrusts in the direction of drive of the ring, as well 95 as in case of the lower bearings carrying part of their weight. The links are connected to the respective bearings by pins e traversing the ends of the links and holes in 100 projections f on the bearings. The links r⁴ 110

may be loosely connected to the shaft g , so that they can rock independently of each other. This construction attains a more advantageous guidance of the roll shafts than heretofore, and provides a much simpler and more economical means for correctly guiding them.

According to another feature of improvement, I provide a rigid bearing frame preferably consisting of a single U-shaped casting or yoke i straddling the casing and receiving the ends of the shaft at opposite sides thereof, so that these ends are assured of parallel bearings, and the number of parts necessary is reduced to the minimum. The bearing end j of each yoke is planed and covered by a bearing cap z , and the projections f for the supporting links are preferably cast integral with the cap so as to support, guide or sustain the bearing from the cap. Each yoke is a relatively heavy casting in order to give not only the strength necessary to rigidity, but the weight desirable to the necessary crushing pressure or inertia. Each yoke is preferably formed with a spring pocket l for receiving the pressure spring, and has a screw threaded aperture m for the corresponding adjusting screw. The spring pocket is formed in a central enlargement n on the outer side of the yoke, which is connected by a rib o and side flanges p with the bearing end j . The side flanges or legs of the yoke preferably converge toward the center as seen in the drawing.

According to another feature of improvement I preferably mount the top shaft so that it can have a downward yield and so it can be adjusted vertically, and so it can move upwardly in case of abnormal stress. This is preferably accomplished by mounting the yoke of the top shaft bearing on the spring S seated on the upper part of the casing and reacting through a seat v against the adjusting screw d of the yoke and thereby supporting the latter from the casing at the desired vertical position relatively to the latter. This provision is sufficient to keep the yoke in its normal position except under exceptional shock or strain, when it may move momentarily to avoid breakage.

To retain the top yoke against falling sidewise, I prefer to provide a guide carried yieldingly by the casing as the upwardly projecting guide s . These guides loosely receive the yoke near its center and limit its motion in forward or rearward direction. For adjusting it vertically, I prefer to use an adjusting screw d screwing into its spring pocket l , which screw may be adjusted directly or through suitable intermediate provisions to lift the yoke more or less from the top casing. As shown, the casing is provided with a projection t , which is cylindrical and has a concave end spaced apart from the washer v against which latter the screw

d acts. The projection t is similar to like projections t^1 and t^2 on the lower casing corresponding to the bearings E^1 and E^2 which projections on the lower casing are used as spring holding provisions for maintaining the spring in proper relation to the yoke in each instance. These are preferably long enough to support the outer end of the yoke through the medium of the spring in case this is desired. The washer v is identical with similar washers which are used between the adjusting screw and spring for each of the lower yokes.

Another feature of improvement consists in utilizing the weight of the lower yokes as an auxiliary means of generating crushing pressure. This I preferably accomplish by utilizing the angularity of the lower bearings so that the weight carried by them tends to force the rolls outwardly against the inner face of the ring preferably by supporting the outer ends of the lower bearings by pivotal connections so disposed that the tendency of these ends to fall under their weight is resisted by the pivotal support in such way as to use the latter in the nature of a toggle joint. As shown, this is done by supporting the outer end of each lower yoke by a link H , which is fulcrumed to the lower casing at I and at the yoke at J , so that it movably supports this end of the yoke from the casing, and tends to move the end of the yoke outwardly as the outward end of the link is depressed. To carry the link H , the yoke is formed with ears w between which the link is pivoted, and the base is formed with ears x between which the link is pivoted.

In machines of this character the crushing pressure has been carried on the bearings. When the machine is empty, the rolls run directly against the face of the ring, but when material is fed on to the inner face the rolls are more or less separated from this face by the thickness of the layer of material being crushed which rests on the face. The greater this thickness the greater the crushing pressure to be resisted by the bearings. My invention provides means for transmitting the resistance of the work being done by one roll on to one or both of the bearings of the other rolls as a crushing force. I prefer to do this by interposing between the bearings of the rolls or a part carrying them, an intermediate movable or yielding thrust or compression member as the link s^4 through which the stress of crushing rolls may intermittently or continuously be transmitted from one bearing to, and be resisted by, the other or others. While the intermediate member may be utilized in any manner for any two or all the other rolls, I prefer to make it a movable link as shown, carrying it from the cap of the top roll C to the cap of the lower rolls respectively so

that it is normally in such position that it will support these and will sustain these in case either moves back a predetermined distance. In such case the intermediate member will be poised between the bearings so as to distribute to each an equal pressure, transmitting the thrust of one to the others. The intermediate link is carried at its upper end in hinged bearings or otherwise freely mounted so that it can adapt itself to variations in the relative positions of the crushing rolls, and thus compensate for the lack of uniformity in their relative movement. It may be any member of suitable properties to properly coat with the bearing portion of any two rolls, or their shafts, with which it co-acts. I prefer to form it as a link hinged to the top bearing and extending toward the other so that it may yield more or less if desirable. This intermediate thrust member makes it possible to so construct the machine that some of the crushing strains are consumed within the ring and rolls. It greatly reduces outside strains and where desired enables the elimination of independent crushing pressure such as that generated by springs and weights.

In operation the ring and rolls will be driven to make the side of the ring near the feed end of the casing move in a downward direction, and at sufficient speed to cause the material to be crushed to be held on the inner face of the ring by centrifugal force. The feed will enter through the chutes, fall on to the inner face of the ring, and be crushed as it passes the rolls. The speed of feed will be adjusted to approximately maintain a predetermined depth of material on the inner face of the ring.

It will be seen that my invention provides improvements which can be variously and advantageously availed of, and it will be understood that the invention is not limited to the particular combination of features and details of construction or arrangement herein described as constituting its preferred form, but that it can be employed in whole or in part according to such modifications as circumstances or the judgment of those skilled in the art may dictate, without departing from the spirit of the invention.

What I claim is:—

1. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which said roll is rotatably mounted, upper roll movable upholding means disposed below the axis of said roll and opposite and beneath said non-rotative means and acting on the latter to hold said roll upwardly toward the inner face of said die to resist a crushing pressure from the latter, and non-rotative supporting means for sustaining said upholding means and from which said upholding means are movably supported. 70

2. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means at each side of said die on which said roll is rotatably mounted, movable upper roll upholding means at each side of said die disposed below the axis of said roll and opposite and beneath said non-rotative means respectively 80 and acting against the latter respectively to hold said roll upwardly toward the inner face of said die to resist a crushing pressure from the latter, and non-rotative supporting means for sustaining said upholding means 90 and from which said upholding means are movably supported. 95

3. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which said roll is rotatably mounted, upper roll pressing means disposed below the axis of said roll and opposite and beneath said non-rotative means and acting on the latter to press said roll upwardly toward the inner face of said die to resist a crushing pressure from the latter, and non-rotative sustaining means for said pressing means and on which said pressing means are sustained. 100

4. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means at each side of said die on which roll is rotatably mounted, upper roll pressing means at each side of said die disposed below the axis of said roll and opposite and beneath said non-rotative means respectively and acting on the latter respectively to press said roll upwardly toward the inner face of said die to resist a crushing pressure from the latter, and non-rotative sustaining means for sustaining said pressing means and on which said pressing means are sustained. 110

120

125

130

5. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which roll 10 is rotatably mounted, movable upper roll holding means disposed below the axis of said roll and above the axis of said die and opposite and beneath said non-rotative means and acting through the latter to hold said roll upwardly toward the inner face of said die to resist a crushing pressure from the latter, and non-rotative sustaining means sustaining said holding means and on which said holding means are sustained.
- 20 6. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means at each side of said die on which said roll is rotatably mounted, movable upper roll holding means at each side of said die disposed below the axis of said roll and above the axis of said die and opposite and beneath said non-rotative means respectively and acting through the latter respectively to hold said roll upwardly toward the inner face of said die to resist a crushing pressure from the latter, and non-rotative sustaining means sustaining said holding means and on which said holding means are sustained.
- 30 7. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which said roll is rotatably mounted, upper roll yielding means disposed below the axis of said roll and above the axis of said die and opposite and beneath said non-rotative means and acting through the latter to hold said roll upwardly toward the inner face of said die to resist a crushing pressure from the latter, and non-rotative sustaining means sustaining said yielding means and on which said yielding means are sustained.
- 40 8. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which roll 50 is rotatably mounted, upper roll yielding means disposed below the axis of said roll and above the axis of said die and opposite and beneath said non-rotative means and acting through the latter to hold said roll upwardly toward the inner face of said die to resist a crushing pressure from the latter, and non-rotative sustaining means sustaining said yielding means and on which said yielding means are sustained.
- 50 9. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which said roll is rotatably mounted, upper roll pivotal 70 pressing means disposed below the axis of said roll and above the axis of said die and opposite and beneath said non-rotative means respectively and acting through the latter respectively to hold said roll upwardly toward the inner face of said die to resist a crushing pressure from the latter, and non-rotative sustaining means sustaining said yielding means and on which said yielding means are sustained.
- 60 10. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means at each side of said die on which said roll is rotatably mounted, pivotal upper roll pressing means 80 at each side of said die disposed below the axis of said roll and opposite and beneath said non-rotative means respectively and acting through the latter respectively to press said roll upwardly toward the inner face of said die to resist a crushing pressure from the latter, and non-rotative sustaining means sustaining said pivotal means and on which said pivotal means are pivotally sustained.
- 70 11. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which said roll is rotatably mounted, upper roll 90 movable compression means disposed below 95
- 80
- 90
- 100
- 110
- 120
- 130

the axis of said roll and above the axis of said die and opposite and beneath said non-rotative means and acting through the latter to hold said roll upwardly toward the inner

5 face of said die to resist a crushing pressure from the latter, and non-rotative sustaining means sustaining said compression means and on which said compression means are sustained.

10 12. In combination, an annular crushing die revolving in an approximately vertical plane and having an internal crushing face, a movable and rotatable crushing roll disposed within the upper part of and eccentric

15 of said die and having a peripheral crushing face reciprocal to the internal face of said die, means for revolving one of said parts, movable non-rotative means at each side of said die on which said roll is rotatably

20 mounted, upper roll movable compression means at each side of said die disposed below the axis of said roll and above the axis of said die and opposite and beneath said non-rotative means respectively and acting

25 through the latter respectively to hold said roll upwardly toward the inner face of said die to resist a crushing pressure from the latter, and non-rotative sustaining means sustaining said compression means and on

30 which said compression means are sustained.

13. In combination, an annular crushing die revolving in an approximately vertical plane and having an internal crushing face, a movable and rotatable crushing roll disposed within the upper part of and eccentric

35 of said die and having a peripheral crushing face reciprocal to the internal face of said die, means for revolving one of said parts, movable non-rotative means on which said

40 roll is rotatably mounted, a pivotal thrust member disposed below the axis of said roll and above the axis of said die and opposite and beneath said non-rotative means and acting through the latter to hold said roll

45 upwardly toward the inner face of said die to resist a crushing pressure from the latter, and non-rotative sustaining means sustaining said thrust member and on which said thrust member is pivotally sustained.

50 14. In combination, an annular crushing die revolving in an approximately vertical plane and having an internal crushing face, a movable and rotatable crushing roll disposed within the upper part of and eccentric

55 of said die and having a peripheral crushing face reciprocal to the internal face of said die, means for revolving one of said parts, movable non-rotative means at each side of said die on which said roll is rotatably mounted,

60 a pivotal thrust member at each side of said die disposed below the axis of said roll and above the axis of said die and opposite and beneath said non-rotative means respectively and acting through the

65 latter respectively to hold said roll upwardly

toward the inner face of said die to resist a crushing pressure from the latter, and non-rotative sustaining means sustaining said thrust members and on which said thrust members are pivotally sustained.

70

15. In combination, an annular crushing die revolving in an approximately vertical plane and having an internal crushing face, a movable and rotatable crushing roll disposed within the upper part of and eccentric of said die and having a peripheral crushing face reciprocal to the internal face of said die, means for revolving one of said parts, movable non-rotative means on which said roll is rotatably mounted, and upper

75

roll rocking holding means below the axis of said roll and opposite and beneath said non-rotative means and extending below the axis of said die acting toward said non-rotative means to hold said roll upwardly toward the

80

inner face of said die to resist a crushing pressure from the latter.

85

16. In combination, an annular crushing die revolving in an approximately vertical plane and having an internal crushing face, a rotatable and obliquely downwardly movable crushing roll disposed within the lower part of and eccentric of said die and having a peripheral crushing face reciprocal to the internal face of said die, means for revolving one of said parts, obliquely downwardly movable non-rotative means on which said roll is rotatably mounted, downwardly lower roll pressing means disposed above the axis of said roll and mounted opposite and above said non-rotative means and acting through the latter to press said roll obliquely downwardly and outwardly toward the inner face of said die to resist a crushing pressure from the latter, and

90

movable non-rotative means for supporting said pressing means.

100

17. In combination, an annular crushing die revolving in an approximately vertical plane and having an internal crushing face, a rotatable and obliquely downwardly and outwardly movable crushing roll disposed within the lower part of and eccentric of said die and having a peripheral crushing

110

face reciprocal to the internal face of said die, means for revolving one of said parts, obliquely downwardly and outwardly movable non-rotative means at each side of said die on which said roll is rotatably mounted,

115

movable lower roll holding means at

120

each side of said die disposed above the axis of said roll and mounted opposite and above said non-rotative means respectively and acting through the latter respectively to hold said roll obliquely downwardly and out-

125

wardly toward the inner face of said die to resist a crushing pressure from the latter, and movable non-rotative means for supporting said pressing means.

18. In combination, an annular crushing

130

- die revolving in an approximately vertical plane and having an internal crushing face, a movable and rotatable crushing roll within and eccentric of said die and having a peripheral crushing face reciprocal to the internal face of said die, means for revolving one of said parts, movable non-rotative means on which said roll is rotatably mounted, pressing means disposed inwardly of the axis of said roll and inwardly of and opposite said non-rotative means and mounted above the axis of said die acting through said non-rotative means for pressing said roll outwardly toward the inner face of said die to resist a crushing pressure therefrom, and non-rotative sustaining means above the axis of said die sustaining said pressing means and by which said pressing means are sustained.
19. In combination, an annular crushing die revolving in an approximately vertical plane and having an internal crushing face, two rotatable crushing rolls movable toward and from one another within and eccentric of said die and each having a peripheral crushing face reciprocal to the internal face of said die, means for revolving one of said parts, movable non-rotative means on which said rolls are rotatably mounted respectively, pressing means at the side of said rolls mounted inwardly of the axes of said rolls, intermediate of and opposite said non-rotative members respectively, and acting through the latter respectively to press said rolls outwardly away from one another to resist a crushing pressure from the inner face of said die, and non-rotative sustaining means sustaining said pressing means and by which said pressing means are sustained.
20. In combination, an annular crushing die revolving in an approximately vertical plane and having an internal crushing face, a rotatable crushing roll within the upper part of and eccentric of said die, a movable and rotatable crushing roll within the lower part of and eccentric of said die, said rolls each having a peripheral crushing face reciprocal to the internal face of said die, means for revolving one of said parts, upper non-rotative sustaining means on which said upper roll is rotatably mounted, movable non-rotative means on which said lower roll is rotatably mounted, and pressing means disposed at the side of said rolls above the axis of said lower roll and opposite and mounted above said movable non-rotative means and acting through the latter to press said lower roll downwardly toward the inner face of said die to resist a crushing pressure from the latter and reacting toward said upper non-rotative member.
21. In combination, an annular crushing die revolving in an approximately vertical plane and having an internal crushing face,

two movable and rotatable crushing rolls within and eccentric of said die and each having a peripheral crushing face reciprocal to the internal face of said die, means for revolving one of said parts, movable non-rotative sustaining means on which said rolls are rotatably mounted respectively, and holding means at the side of said rolls mounted inwardly of the axes of said rolls and opposite and intermediate of said non-rotative means and acting on the latter to hold said rolls outwardly away from one another to resist a crushing pressure from the inner face of said die and sustained by and reacting on said non-rotative means to transmit the stress of one thereof to another thereof.

22. In combination, an annular crushing die revolving in an approximately vertical plane and having an internal crushing face, three rotatable crushing rolls two movable toward and from one another within and eccentric of said die and each having a peripheral crushing face reciprocal to the internal face of said die, means for revolving one of said parts, non-rotative means on which one of said rolls is rotatably mounted, movable non-rotative means on which said movable rolls are rotatably mounted respectively, pressing means disposed at the side of said rolls intermediate of the axes of said rolls and mounted intermediate of and above and opposite said movable non-rotative means respectively and acting on the latter respectively to press said movable rolls outwardly away from one another toward the inner face of said die to resist a crushing pressure therefrom, and non-rotative sustaining means sustaining said pressing means and on which said pressing means are sustained.

23. In combination, an annular crushing die revolving in an approximately vertical plane, and having an internal crushing face, three rotatable crushing rolls movable toward and from each other within and eccentric of said die and each having a peripheral crushing face reciprocal to the internal face of said die, means for revolving one of said parts, movable non-rotative means on which said rolls are rotatably mounted respectively, holding means disposed opposite and intermediate of said non-rotative means and mounted intermediate of the axes of said rolls and acting through said non-rotative means respectively to hold said rolls outwardly away from one another to resist a crushing pressure from the inner face of said die, and non-rotative sustaining means sustaining said holding means and on which said holding means are sustained.

24. In combination, an annular crushing die having an internal crushing face, three rotatable crushing rolls movable toward and from each other within and eccentric of said die and each having a peripheral crushing

face reciprocal to the internal face of said die, means for revolving one of said parts, movable non-rotative sustaining means at the side of said die on which said rolls are 5 rotatably mounted respectively, and movable thrust means at the side of said rolls mounted intermediate of the axes of said rolls, and opposite and intermediate of said movable means respectively, and acting against the 10 latter to hold said rolls outwardly toward the inner face of said die to resist a crushing

pressure from the latter and sustained by and reacting from one to another of said movable means to transmit the inward stress of one to another of said rolls.

15

In witness whereof, I have hereunto signed my name in the presence of two subscribing witnesses.
